UNITED STATES PATENT OFFICE.

SWITS CONDÉ, OF OSWEGO, NEW YORK.

CIRCULAR-KNITTING MACHINE.

SPECIFICATION forming part of Letters Patent No. 245,135, dated August 2, 1881.

Application filed April 26, 1881. (No model.)

To all whom it may concern:

Be it known that I, SWITS CONDÉ, of Oswego, in the county of Oswego, in the State of New York, have invented new and useful Improvements in Circular-Knitting Machines, of which the following, taken in connection with the accompanying drawings, is a full, clear, and exact description.

This invention consists in novel means of producing on a knitting-machine multiple-threaded fabric, striped longitudinally, without carrying thereon loose threads or varying the texture of the fabric.

The invention is fully illustrated in the accompanying drawings, wherein Figure 1 is a side view of the mechanism employed for carrying two threads of different colors simultaneously into the knitting-needles in such a manner as to produce vertical stripes in the fabric. Figs. 2 and 3 are front and plan views, respectively, of the aforesaid mechanism; and Figs. 4 and 5 are detail views illustrating the effect of the same.

Similar letters of reference indicate corresponding parts.

A represents the usual rotary cylinder, which carries the bearded knitting-needles N.

L denotes the loop-wheel or burr, arranged on the outside of the needle-cylinder to force 30 into the beards of the needles the thread or yarn guided thereto by the bar a, which is fixed stationary at the side of the standard s, and has its forward extremity in proximity to the loop-wheel, and provided with an eye through which the thread passes on its way 35 to the loop-wheel.

Striped fabric has been produced by various constructions and arrangements of the aforesaid devices alone, but in many instances the effect has been accomplished simply by alternately dropping or carrying one of the threads across the outside of the beard of the needles, while another thread was forced into the beards and formed a single-threaded stitch, thus carrying at intervals a loose thread on the back of the fabric and varying the texture thereof. It is to obviate these defects which my invention has chiefly for its object; and to that end I employ, in connection with the ordinary loop-wheel and the stationary thread-guide a, two or more thread-guides arranged to oscillate or

vibrate vertically or lengthwise to the needles, each of said vibratory thread-guides being provided with a differently-colored thread, which passes with the thread of the other vibratory 55 thread-guide through the eye of the stationary thread-guide and to the loop-wheel, which carries both of said threads or yarns simultaneously into the beards of the needles. The upward movement of either of the vibratory thread-guides throws its respective thread above the other thread, and at the same time increases the tension on said elevated thread so as to cause the same to be drawn to the front within the beard of the needle, as illustrated in Figs. 60 65 4 and 5 of the drawings. The previously-formed loops, being drawn over the said threads in the needles, forms the latter into a new loop, presenting different colors at the front and back of the fabric. It is obvious that by elevating 70 the vibratory thread-guides alternately and at certain intervals vertical stripes are produced in the fabric, and since both threads invariably enter the beards of the needles no loose threads are carried on the exterior of the fabric, and the fabric is maintained at a uniform 75 texture. The stripes, however, will be more or less variegated or mottled, inasmuch as small portions of the rear thread will occasionally be visible between the front threads.

In the drawings hereto annexed, b and b' represent the vibratory thread-guides, arranged by the side of the stationary thread-guide a, the former being of a form similar to that of the latter, but pivoted thereon, as shown at r.

Each of the vibratory thread-guides is provided with a differently-colored thread, and both threads pass through the eye of the stationary guide a, and are simultaneously carried into the beards of the needles by the loop-wheel L.

The free ends of the vibratory thread-guides b b' are supported and guided by an arm, i, secured to the standard s, and having pins k k, between which the thread-guides b b' play.

On the arm i is pivoted a rock-arm, c, which engages the under side of the thread-guides b b'. The rock-arm c receives motion from a pitman, d, connected to a lever, e, which is fulcrumed on the table or platform of the machine 100 in front of the needle-cylinder, as shown at n, and has its opposite free end underneath the

needle-cylinder A, and provided thereat with a friction-roller, v.

The base of the needle-cylinder A is provided with cams f, in the form of downward projections, which depress the free end of the lever e intermittently when the cylinder A is in motion. The alternate depression and elevation of the lever e causes the opposite end thereof to impart a reciprocal movement to the pitman 15 d, which, in turn, actuates the rock-arm c. The latter, engaging at opposite sides of its pivot the thread-guides b b', lifts the said guides alternately. The elevated thread-guide throws its thread above that of the other thread-guide, and simultaneously increases the tension on the elevated thread within the needle, thereby drawing said thread toward the front of the machine, while the other thread is crowded rearward, and is so retained by the previously-20 formed loops of the fabric, which is drawn over said threads and off the cylinder in the usual and well-known manner.

The alternation of the within-described movement of the thread-guides b b' brings the different-colored threads alternately to the front

of the fabric, and thus produces longitudinal stripes, as before described, without carrying loose threads on the surface of the fabric or varying the texture thereof.

The lengths of the cams f and the distance 30 between them may be regulated to obtain the desired width of the stripes at will.

Having described my invention, what I claim as new, and desire to secure by Letters Patent, is—

35 In combination with the needles N, loop-wheel L, and the stationary thread-guide a, the hinged thread-guides b b', rock-arm c, pitman d, lever e, and cylinder A, provided with cams f, substantially in the manner described and shown, for the purpose set forth.

In testimony whereof I have hereunto signed my name and affixed my seal in the presence of two attesting witnesses, at Oswego, in the county of Oswego, in the State of New York, 45 this 18th day of April, 1881.

SWITS CONDÉ. [L.S.]
